DECORATIVE LIGHT BULB OR SIMILAR
ARTICLE

Joseph J. Librizzi, Bronxville, N. Y.

Application April 27, 1951, Serial No. 14,987

Term of patent 14 years

(Cl. D26—8)

To all whom it may concern:

Be it known that I, Joseph J. Librizzi, citizen of the United States, and a resident of Bronxville, county of Westchester, State of New York, have invented a new, original, and ornamental Design for Decorative Light Bulb or Similar Article, of which the following is a specification, reference being had to the accompanying drawings, forming a part thereof.

Fig. 1 is a top plan view of a decorative light bulb or similar article illustrating my new design;

Fig. 2 is a side elevational view of the decorative light bulb or similar article illustrated in Fig. 1;

Fig. 3 is a side elevational view showing the opposite side of the decorative light bulb or similar article illustrated in Fig. 2; and

Fig. 4 is a fragmentary sectional view through a portion of the decorative light bulb or similar article.

The decorative light bulb or similar article illustrated is comprised of light-transmitting material.

I claim:

The ornamental design for a decorative light bulb or similar article, substantially as shown and described.

JOSEPH J. LIBRIZZI.
